UNITED STATES PATENT OFFICE.

MAURICE SIMON, OF ST. LOUIS, MISSOURI.

ELECTRIC WATER-HEATER.

1,191,743.

Specification of Letters Patent. Patented July 18, 1916.

Application filed July 26, 1915. Serial No. 41,896.

To all whom it may concern:

Be it known that I, MAURICE SIMON, a citizen of the United States, residing in the city of St. Louis and State of Missouri, have invented a new and useful Electric Water-
5 Heater, of which the following is a specification.

This invention relates to improvements in electric water heaters and consists in the 10 novel design, construction and arrangement of parts hereinafter more fully disclosed.

An object of the invention is to provide a water heater including a chamber wherein the water is heated by passing an electrical current therethrough with means for varying 15 the amount of electrical resistance so that the degree to which the water may be heated may be varied.

Another object of the invention is to provide 20 a heating chamber with means for introducing and withdrawing water thereto and therefrom, with provision for passing an electrical current through the volume of water as it passes through the heating chamber.

Another object of the invention is to construct 25 a water heater comprising a heating chamber with provision for passing an electrical current through the volume of water in said chamber, in combination with automatic means for making and breaking the electrical circuit.

Another object of the invention is to equip 30 a heater of the type mentioned with automatic means for breaking the electrical circuit when a predetermined temperature has been attained in the heating chamber of the heater.

With the foregoing specifically mentioned 35 objects in view, and additional features and advantages obtainable from the construction which will be apparent without specific mention, I have designed, combined and arranged the various elements and devices hereinafter more fully disclosed, reference being made to the accompanying drawings, in which—

Figure 1 is a vertical section through the heating chamber with the coöperating parts associated therewith clearly illustrating the 40 details of construction of an embodiment of the invention. Fig. 2 is a cross section through the heater taken substantially on the line 2—2 of Fig. 1. Fig. 3 is a cross section taken substantially on the line 3—3 of Fig. 1. Fig. 4 is a detail view illustrating the 45 details of the circuit breaker which is

under control of the thermostatic device for breaking the circuit when a predetermined temperature has been attained in the heater. Fig. 5 is a detailed view illustrating the 60 details of construction of the automatically operated switch for controlling the supply of electrical energy to the heater. Fig. 6 is a diagrammatic view of the electrical circuit with the devices for controlling the 65 same for energizing the heater.

In the preferred embodiment of the invention illustrated in the drawings the apparatus is shown as comprising a cylindrical case 1 which is provided with an interior 70 lining 2 of non-conducting material. It is contemplated that in practice the insulation of the interior of the case shall be effected by coating the inner wall of the case 1 with an enamel lining, or a separate lining of 75 rubber may be utilized if desired.

The case 1 is provided at each end with an outwardly extending annular flange 3, the ends of the case being closed by end plates 4 and 5 respectively. The plates 4 and 5 are secured in position by bolts 6, which pass through openings in said plates adjacent to the periphery thereof and through the flanges 3. Between the end plates and the ends of the case 1 are inter- 80 posed sheets 2 of rubber or other insulating material, and insulating sleeves 8 surrounding the stem of the bolts 6 and within the 85 openings through the plates are provided.

Secured within the case 1 are a series of 90 cylinders 9 formed of porcelain or other insulating material. The cylinders 9 are of decreasing diameters and each cylinder is provided with flanges 10 at one end thereof. The cylinders are arranged in a concentric 95 series and are of a length slightly less than the length of the case 1. The series of cylinders 9 are alternately turned with the flanges 10 abutting against the respective end plates 4 and are retained in position by a series of concentric rings 11, there being provided insulating rings 12 between the rings 11 and the face of the flanges 10, and also spacing rings 13 for retaining the cylinders 9 in the adjustment clearly illustrated 100 in Fig. 2.

The water to be heated is introduced through a supply passage 14 into an annular chamber 15 formed in a boss 16 integral with the side wall of the case 1, through 110 which it passes through a series of openings 17 into the case and flows through the tor-

tuous passage formed by the cylinders 9 as indicated by the arrows to a discharge passage 18 which is connected into a head-piece 19 which forms the continuation of the central one of the cylinders 9.

The rings 11 are of electrical conducting material and certain of said rings 11 constitute one pole of the electrical circuit that passes through the volume of water within the heater case and the metallic cylinder 20, projecting into the central one of the cylinders 9, constitutes the other pole of the electrical circuit. The rings 11 are retained in position by bolts 21 which pass through the end plates 4 and 5 and are surrounded by insulating sleeves 22.

It will be noted by reference to Fig. 1 of the drawing that four of the retaining rings 11 are placed in the electrical circuit having lead wires attached to the retaining bolts for said rings, which bolts are equipped to constitute binding posts for the wire terminals. The arrangement is such that the electrical current enters the water at four different radial points, so that the amount of the water between the poles of the circuit passing therethrough may be varied and thereby the amount of resistance through which the current will pass may be regulated. It will, of course, be understood that water, depending upon its degree of purity, offers greater or less resistance to the passage of the current and this means of introducing the current provides for coördinating the resistance relative to the determined resistance of a unit of volume of the water; it also provides for the heating of the water to various degrees.

The optional control of the point of the introduction of the current into the water is effected through a four point switch 23 connected at one terminal to a lead wire 24 of the circuit and at the other terminal with a series of lead wires 25, which are placed in circuit with the respective rings 11. The opposite pole 20 of the circuit is in electrical connection with the other lead wire 26 of the main circuit, the two main lead wires 24 and 26 terminating in a screw socket 27 for attachment at a remote point to the source of electrical energy.

Interposed in the lead 24 of the main circuit is a circuit breaker 28. In the embodiment of the invention shown the circuit breaker 28 comprises a movable member 29 and a bifurcated extremity 30. The member 29 is movably mounted in brackets 31 formed on the plate 5. The member 29 is insulated from the extremity 30. The two ends of the lead 24 entering the circuit breaker are attached to plates 33 arranged to be mounted upon a bracket 34 of insulating material, with an insulating spacing rib 35 between the plates. The member 29 is normally actuated away from the plates 33

by an expansion spring 36 which bears at one end against the face of one of the brackets 31 and at the other end against a flange 37 integral with the stem of the member 29. The normal position of the circuit breaker, therefore, is open and the circuit is closed only when water is withdrawn from the heater, thereby causing the operation of the water pressure valve 38 which is provided with a stem 39 which is in axial alinement with the stem of the member 29. The stem 39 of the water pressure valve is moved sufficiently when water is withdrawn from the heater to move the bifurcated extremity 30 of the member 29 into contact respectively with the plates 33, thereby closing the circuit through said extremity. As the details of construction of the water pressure valve are no part of the present invention and as the construction is well understood in the art, it is unnecessary to explain its operation in detail, its action being simply to move the terminal 30 into contact with the plates 33 to close the circuit and to maintain the circuit closed so long as water is being withdrawn from the heater, the circuit being broken upon the return of the member 29 to normal position as soon as the stem 39 moves inwardly to the valve case of the valve 38, when the discharge of the water from the heater is closed by closing off the service faucet in the supply system, as will be readily understood.

In order to open the supply circuit when a predetermined maximum temperature of the water has been attained I provide a second circuit breaker 40 in the circuit. The circuit breaker 40 comprises terminal plates 41 arranged on an insulating bracket 42 having an insulating spacing rib 43 between the plates. A lever 44, provided at its extremity with a contact member 45 is pivoted in brackets 46 formed on a head plate 47 adjusted at the end of the member 19. The lever 44 is normally held in depressed position. Said lever 44 is in adjustable relationship with a second lever 48 which is pivoted in brackets 49. Through the short arm of the lever 44 is threaded an adjustable stem 50 which bears against the extremity of the lever 48. In contact with the lever 48 and actuating it outwardly is a stem 51.

The stem 51 is controlled by a thermostatic device which is of substantially the same construction as that shown and fully described in my copending application filed June 1, 1915, Serial No. 31,460. The stem 51 normally projects beyond the end of the cylinder 20, but under the influence of heat from the water surrounding the cylinder 20 the tendency of the stem is to recede within the case. The stem 51, normally bearing against the lever 48 and through the connection 50 with the short arm of the lever 44, holds the extremity of the long arm de-

pressed sufficiently to maintain the member 45 in contact with the plates 41, thereby maintaining the circuit closed until the stem 51 has receded sufficiently to release the short 5 arm of the lever 44, whereupon expansion springs 52 move the lever 44 and its extremity 45 away from the plates 41 opening the circuit. As the details of construction of the thermostatic device, whereby the movement of the stem 51 is controlled, are no part of the present invention and are fully disclosed in the copending application referred to, it is unnecessary to describe the construction at length.

15 From the foregoing description it will be understood that the chief features of the operation of the heater of the present invention are as follows: When water is withdrawn from the discharge passage 18 the 20 pressure in the supply passage 14 is reduced and the pressure operated valve 38 actuates the circuit breaker 28 to close the circuit, it being understood that by means of the four point switch 23 the point at which the current 25 enters the case has been determined. The current entering the case through the selected one of the rings 11 passes through the water to the opposite pole 20, thus heating the water and incidentally purifying the 30 water by a known electrical action. When the water has been heated to a predetermined degree the thermostatic device will so act as to actuate the circuit breaker 40 cutting off the supply of current, the circuit remaining 35 open until the temperature of the water has dropped sufficiently to cause the thermostatic device to again close the circuit. In this construction, as the water itself constitutes the resistance element, the entire electrical 40 energy will be utilized in the heating of the water without loss from radiation.

It will be understood that numerous changes in details of construction may be made without departing from the spirit and 45 scope of my invention. Therefore, I do not desire to limit myself to the exact details of construction shown and described, but

What I desire to claim and secure by Letters Patent, is:—

1. A water heater comprising a case, a water inlet to said case, a water outlet from said case, a series of baffle walls in the form of open-ended spaced cylinders of insulating material, a series of terminals for one end of an electric circuit, a single terminal constituting the other end of the electric circuit, said terminals entering said case, and a switch for placing selected ones of 55 said first-named series of terminals in circuit, substantially as specified.

2. A water heater, comprising a case, a water inlet to said case, a water outlet from said case, and a series of baffle walls in the 60 form of open-ended cylinders of insulating

material interspaced and oppositely arranged in said case for deflecting the flow of water therethrough, in combination with an electrical terminal at one point in said case, and a second electrical terminal at another 70 point in said case, the said baffle walls being interposed between said terminals.

3. A water heater, comprising a case, a water inlet to said case, a water outlet from said case, a series of insulated baffle walls 75 mounted in said case and constituting deflectors for directing a tortuous flow of the water in said case, a series of terminals for one end of an electrical circuit entering said case, a single terminal constituting the other 80 end of the electrical circuit entering said case, and an automatic circuit breaker in said circuit operable effectively to close the circuit when water is withdrawn from said outlet passage, substantially as specified. 85

4. A water heater comprising a case, an inlet passage to said case and an outlet passage from said case, a series of open-ended cylinders of insulating material forming 90 communicating chambers, a series of terminals for one end of an electric circuit, each of said terminals of the series being arranged in communication with separate ones of said communicating chambers, a single terminal constituting the other end of the circuit entering said case, an optionally operable controlling device for cutting in one end of the circuit selectively to said first-named terminals, and an automatic circuit breaker for 95 closing the circuit, substantially as specified. 100

5. A water heater, comprising a case, an inlet passage to said case and an outlet passage from said case, an electrically energized circuit entering said case at separated points, an automatically operated circuit breaker in said circuit, a series of insulating baffle walls between the points at which the circuit enters the case, and a thermostatic device adapted to make and break said circuit independent of said automatic circuit breaker, substantially as specified. 105

6. A water heater, comprising a case, a series of concentric cylinders of varying diameters located in said case and adapted 115 to constitute baffle walls for causing a deflected flow of water entering said case and passing therefrom, a series of electrical terminals entering said case and between different ones of said cylinders, and a second terminal located within said case and separated therefrom. 120

7. A water heater, comprising a case, a chamber in communication with said case through a series of ports, a supply passage entering said chamber, an outlet passage from said case, an actuating circuit for passing an electrical current through the water contained in said case, an automatic circuit breaker operable effectively to close said circuit when water is withdrawn from said case, 130

and a device under the influence of heat from the water in said case for breaking said circuit when a predetermined maximum degree of temperature has been attained in said case.

8. A water heater, comprising a case, partition walls in said case for separating the case into communicating compartments, an electrical terminal of the supply circuit entering said case, a series of terminals in communication with separate ones of said compartments, and optionally operable means for placing selected ones of said terminals in circuit with the main supply circuit, substantially as specified.
10. A water heater comprising a case, a series of open-ended oppositely arranged and interspaced cylinders of insulating material mounted in said case, electrodes entering 30 said case, a supply passage for said case, an outlet passage in said case, a circuit for energizing said electrodes, and means in said circuit operable on the withdrawal of water from said outlet passage for energizing said 35 circuit, substantially as specified.

9. A water heater comprising a case, a series of partition walls formed of insulating material arranged in said case, and dividing the same into communicating compartments, an electrode in communication with each of said separate compartments, a stationary electrode spaced from said first-
- 20

named electrodes, and an optionally operable switch device for placing selected ones of said first-named electrodes in circuit, substantially as specified.

10. A water heater comprising a case, a series of open-ended oppositely arranged and interspaced cylinders of insulating material mounted in said case, electrodes entering 30 said case, a supply passage for said case, an outlet passage in said case, a circuit for energizing said electrodes, and means in said circuit operable on the withdrawal of water from said outlet passage for energizing said 35 circuit, substantially as specified.

In witness whereof, I have signed this specification in the presence of two subscribing witnesses.

MAURICE SIMON.
